Patented Aug. 26, 1913.

UNITED STATES PATENT OFFICE.

FREDERIK VAN GELDEREN, OF CHICAGO, ILLINOIS, ASSIGNOR TO LINDSAY LIGHT COMPANY, OF CHICAGO, ILLINOIS, A CORPORATION OF ILLINOIS.

LAMP.

1,071,372.

Specification of Letters Patent. Patented Aug. 26, 1913.

Application filed April 16, 1913. Serial No. 761,604.

To all whom it may concern:

Be it known that I, FREDERIK VAN GELDEREN, a subject of the Queen of the Netherlands, residing at Chicago, in the county of Cook and State of Illinois, have invented a new and useful Lamp, of which the following is a specification.

My invention relates particularly to gas-lamps; and my primary object is to provide a lamp of improved general construction and operation, which shall be of compact form, neat appearance, and capable of being manufactured at small cost.

The invention is illustrated in its preferred embodiment in the accompanying drawing, in which—

Figure 1 represents a broken vertical sectional view of a lamp constructed in accordance with my invention, the section being taken as indicated at line 1 of Fig. 2; Fig. 2, a horizontal section taken as indicated at line 2 of Fig. 1; Fig. 3, a broken vertical section taken as indicated at line 3 of Fig. 2; and Fig. 4, a broken elevational view, 25 showing the manner in which an air-deflecting shield employed is detachably connected with the lamp-body.

In the form illustrated, the invention is embodied in a lamp comprising a body A equipped at its lower portion with a globe-holder A'; a gas-pipe B on which the lamp-body is suspended and which is fitted with a burner B' equipped with a mantle B²; and a globe C suspended from the globe-holder A'.

The lamp-body comprises an outer approximately frusto-conical shell 1, the enlarged lower end of which is equipped with the globe-holder A'; and an inner shell 2 which conforms generally to the shape of the member 1, but is separated therefrom by a small annular space 3. The frusto-conical member 1 has its apex portion 1^a struck or dished downwardly, thus providing a housed neck-portion having an in-turned flange 1^b, through which extends a threaded portion 4 of the pipe B. The member 2 has its upper end provided with an in-turned flange 2^a through which the threaded portion 4 of the pipe B extends. The flanges 1^b and 2^a are clamped between nuts 5 screwed on the portion 4 of the pipe.

Above the flanges mentioned, the pipe B is provided with a fitting 6, the passage 55 through which is controlled by a needle-

valve 7; and above the fitting 6 is another fitting 8, the passage through which is controlled by a plug valve 9, which is operated by chains 10. A pilot burner-tube 11 is connected with the fitting 8, and serves to maintain a small flame in the vicinity of the mantle B². The fitting 6 is equipped with a sleeve or air-shutter 6^a which controls the admission of air to the Bunsen burner. Near the lower portion of the lamp-body, 65 the outer shell 1 flares outwardly and downwardly, as indicated at 1^c; and the globe-support is carried by the portion 1^c of the outer shell. The globe-holder A' may be of any desired construction. It is shown as an annular member 12 fitted with set-screws 13 adapted to engage the external bead with which the neck-portion of the globe is provided.

The lower end of the member 2 is spun 75 over the outer edge of an annular plate 14 which has a down-turned flange 14^a over which is telescopically fitted the upper cylindrical portion of a shield 15 whose lower end flares outwardly or is frusto-conical. 80 The member 14^a is provided with lateral studs 16 which engage bayonet slots 16^a with which the upper portion of the member 15 is provided, as shown in Fig. 4. The bayonet slots 16^a are partially formed by striking the metal of the member 15 outwardly, as indicated at 16^b, the outwardly struck portion of the metal being adapted to slip over the end of the stud 16 when the shield is removed.

The walls of the members 1 and 2 are cut away, as indicated at points 17, to afford outlets for the products of combustion. At the upper margins of the cut-away places, the metal of the two walls is curved outwardly, as indicated at 17^a in Fig. 3. Encircling the member 1 near its base portion is a sheet metal member 18 of annular form, and having a contracted lower end portion 18^a. The member 18 flares upwardly and outwardly, thus forming with the openings 17 channels 19 through which the products of combustion may escape. The member 18 may be given an ornamental appearance. It not only serves to direct the products of combustion outwardly, but also as a shield for the openings 17 which are thus practically concealed from view.

The portion 1^c of the member 1 is provided with air-admission openings 20. As 110

noted by the arrows in Fig. 1, the entering air is deflected by the shield 15 so as not to impinge directly against the mantle.

The member 18 is detachable, its contracted lower portion 18^a being provided internally with vertical grooves 18^b which permit the member to be slipped over lateral studs 21 carried by the base portion of the member 1. After being slipped over the studs 21, the member 18 is rotated, thus bringing the studs above the annular shoulder 22, so that the outer shield 18 is thus secured in place.

The construction described is simple, capable of being manufactured at small cost, and presents a good appearance. Moreover, as experience has demonstrated, the improved lamp operates in a thoroughly efficient manner.

The foregoing detailed description has been given for clearness of understanding only, and no unnecessary limitation should be understood therefrom, but the appended claims should be construed as broadly as permissible, in view of the prior art.

What I regard as new and desire to secure by Letters Patent is:

1. In a gas-lamp, the combination with a gas-pipe equipped at its lower end with a burner, of a body comprising inner and outer shells having contracted upper ends with openings therethrough for said gas-pipe, means securing the body to said pipe at the point where the pipe passes through said contracted ends, said body having lateral openings with the metal at the upper portions of said openings curved outwardly, and an upwardly and outwardly flaring shield encircling said body and partially guarding said openings.

2. In a lamp, the combination of a gas-pipe, a body comprising an outer frusto-conical shell having its contracted upper end portion struck inwardly and provided with an inturned flange with an opening therethrough admitting said pipe, an inner frusto-conical shell having an inturned flange disposed below said first-named flange and having an opening admitting said pipe, nuts on said pipe between which said flanges are clamped, said shells having a lateral opening, and a shield encircling the outer shell and forming with said opening a channel for the escape of products of combustion.

3. In a lamp, the combination of a gas-pipe, a body comprising an outer frusto-conical shell having its contracted upper end portion struck inwardly and provided with an inturned flange with an opening therethrough admitting said pipe, an inner frusto-conical shell having an inturned flange disposed below said first-named flange and having an opening admitting said pipe, nuts on said pipe between which said flanges are clamped, said shells having a lateral

opening, and a removable shield encircling the outer shell and forming with said opening a channel for the escape of products of combustion.

4. In a lamp, the combination of a gas-pipe equipped at its lower end with a burner, of a body comprising an outer frusto-conical shell having its lower portion enlarged and provided with air inlets, a globe-support carried by the enlarged portion of said shell, an inner shell having its walls disposed near the walls of said outer shell, the upper portions of said shells being contracted and joined to said pipe, said shells having a lateral opening for the escape of products of combustion, an upwardly flaring external shield encircling the outer shell and partially guarding said opening, and an inner shield depending from said inner shell and guarding the burner.

5. In a gas-lamp, the combination of a gas-pipe equipped at its lower end with a burner, a body comprising an outer frusto-conical shell having its upper contracted end struck downwardly and inwardly, an inner shell conforming generally to the shape of the outer shell and having an inturned upper flange, the contracted portions of said shells being connected with said pipe, a globe-holder carried by the lower portion of the outer shell, a burner shield carried by the lower portion of the inner shell, and gas regulating means connected with said pipe above said outer shell.

6. In a gas-lamp, the combination of a gas-pipe equipped at its lower end with a burner, a body comprising an outer frusto-conical shell having its upper contracted end struck downwardly and inwardly, an inner shell conforming generally to the shape of the outer shell and having an inturned upper flange, the contracted portions of said shells being connected with said pipe, a globe-holder carried by the lower portion of the outer shell, a burner shield carried by the lower portion of the inner shell, said shells being provided with a lateral outlet, and gas-regulating means connected with said pipe above said outer shell.

7. In a gas-lamp, the combination of a gas-pipe equipped at its lower end with a burner, a body comprising an outer frusto-conical shell having its upper contracted end struck downwardly and inwardly, an inner shell conforming generally to the shape of the outer shell and having an inturned upper flange, the contracted portions of said shells being connected with said pipe, a globe-holder carried by the lower portion of the outer shell, a burner shield carried by the lower portion of the inner shell, said shells being provided with a lateral outlet, an upwardly and outwardly flaring external shield encircling said outer shell and partially guarding said opening, and gas-regulating

means connected with said pipe above said outer shell.

8. In a gas-lamp, the combination of a gas-pipe equipped at its lower end with a burner, of a body composed of upwardly converging inner and outer shells having contracted upper ends provided with openings through which the gas-pipe extends, means connecting the contracted upper ends 5 of said shells with the gas-pipe, said shells having a lateral outlet for the products of combustion, gas-regulating means connected

with said pipe above said body, a globe-support carried by the lower portion of the outer shell, a burner-shield carried by the lower portion of the inner shell, and an upwardly and outwardly flaring outer shield having its lower portion closely encircling the outer shell below the plane of said lateral opening.

FREDERIK VAN GELDEREN.
